VIDEO-FREQUENCY SIGNAL-TRANSLATING
SYSTEMJohn C. Wilson, Bayside, N. Y., assignor to Hazel-
tine Corporation, a corporation of Delaware

Application June 9, 1939, Serial No. 278,316

8 Claims. (Cl. 178—7.3)

This invention relates to television video-frequency signal-translating systems and, more particularly, to such systems including provisions for controlling the background illumination of the reproduced scene.

In accordance with the present television practice, a transmitted signal comprises picture or video-frequency components representing variations in light values of successive areas of an image being transmitted and synchronizing-frequency components which correspond to initiations of successive lines and fields in the scanning of the image. The latter components ordinarily have amplitude values outside of the amplitude range of the video-frequency components. There is usually developed at the transmitter a unidirectional voltage which corresponds to the average background illumination of the scene, but this voltage is lost if the video-frequency signal is passed through alternating current amplifiers at the transmitter or the receiver. However, the signal as received includes a component from which the unidirectional voltage representative of background illumination may be derived and which is not lost when the video-frequency signal is translated by an alternating current amplifier.

A signal-reproducing device, such as a cathode-ray tube, is employed at the receiver and the cathode ray is deflected therein to scan, in a series of parallel lines, a fluorescent screen upon which the image of the transmitted scene is reconstructed. The synchronizing-frequency components of the received signal are utilized to control the scanning apparatus so as to synchronize its operation with that of similar apparatus utilized at the transmitter in developing the signal. The intensity of the cathode ray is controlled by the picture or video-frequency components of the signal as well as by the unidirectional-background-illumination voltage developed in the receiver, thereby to reconstruct the scene.

Heretofore, arrangements have been provided for detecting a received video-frequency signal to derive therefrom a unidirectional voltage representative of the background illumination. Certain of the systems of the prior art, however, have been subject to certain objectionable features including the fact that the unidirectional voltages developed thereby are not exactly equal to the peak value of the video-frequency signal on the black side of the zero axis, so that precise stabilization of the signal, which effectively reinserts the background-illumination compo-

nent, cannot be obtained. While certain arrangements for overcoming this defect have been devised, these arrangements have something to be desired, for example, they may require relatively complicated or expensive additional apparatus, such as separate amplifying channels for the background-voltage developing means.

It is an object of the present invention to provide in a television signal-receiving system improved means for developing and reinserting the background-illumination component in the video-frequency signal being translated.

In accordance with the present invention, there is provided a video-frequency signal-translating system which comprises an amplifier having an input circuit which is adapted to have impressed thereon an unstabilized video-frequency signal having its background illumination represented by the peak value thereof on the black side of its zero axis. A grid-leak resistor and an output circuit are provided for the amplifier and means are coupled to the output circuit for deriving only the alternating current component therein. The system includes means connected to this last-mentioned means which is responsive to said peak value of said signal on the black side of its zero axis for developing a unidirectional voltage proportional thereto. Means are further provided for applying said unidirectional voltage to said input circuit in series with the grid-leak resistor to reinsert the background-illumination component in the signal translated by said system. Preferably, adjustable means, such as a voltage-divider resistor, are included in the output circuit for selecting a portion of the signal-output voltage of the amplifier and the unidirectional-voltage developing means comprises a diode rectifier coupled to the voltage-divider resistor. An initial fixed-bias voltage may be applied to the input circuit of the amplifier and the unidirectional voltage developed by the rectifier may be applied in opposition to the fixed-bias voltage.

For a better understanding of the invention, together with other and further objects thereof, reference is had to the following description taken in connection with the accompanying drawing, and its scope will be pointed out in the appended claims.

In the accompanying drawing, the single figure is a circuit diagram, partially schematic, of a television receiving system including circuits embodying the present invention.

Referring now more particularly to the drawing, the system there illustrated comprises a re-

ceiver of the superheterodyne type including an antenna system 10, 11 connected to a radio-frequency amplifier 12 to which is connected, in cascade, in the order named, an oscillator-modulator 13, an intermediate-frequency amplifier 14, a detector and A. V. C. supply 15, a video-frequency amplifier 16, a second stage of video-frequency amplification 17 embodying the present invention and which will be hereinafter described in detail, and a signal-reproducing device 18 such as a cathode-ray signal-reproducing tube.

For developing saw-tooth waves for the scanning elements included in the device 18, there are provided a line-frequency generator 19 and a field-frequency generator 20. The output circuit of the amplifier 17 is coupled to these generators for maintaining them insynchronism with the scanning operations at the transmitter while the output circuits of generators 19 and 20 are connected to the scanning elements of the device 18 for developing scanning fields in a conventional manner.

The elements or components 10-16, inclusive, and 18-20, inclusive, may all be of conventional well-known construction so that detailed illustrations and descriptions thereof are deemed unnecessary herein.

Since the system thus far described is, in general, conventional and well understood in the art, a detailed explanation of its general operation is deemed unnecessary. Briefly, however, signals intercepted by the antenna circuit 10, 11 are selected and amplified in the radio-frequency amplifier 12 and supplied to the oscillator-modulator 13 wherein they are converted to intermediate-frequency signals which, in turn, are selectively amplified in the intermediate-frequency amplifier 14 and delivered to the detector 15. The modulation components of the signal are derived by the detector 15 and are supplied to the video-frequency amplifier 16 wherein they are amplified and from which they are supplied to the amplifier stage 17 for further amplification and for reinsertion of the background-illumination component in accordance with the present invention, as will be presently further described. The video-frequency signals are thereupon supplied to a control element of the signal-reproducing device 18. A. V. C. bias voltage developed by the detector and A. V. C. supply 15 is applied to the control electrodes of one or more of the tubes of the preceding stages of the system and serves to maintain the signal amplitude of the output of the amplifier 14 within a relatively narrow range or substantially constant for a wide range of received signal intensities.

The intensity of the scanning beam in the image-reproducing device 18, for example, the cathode ray, where a cathode-ray signal-reproducing tube is employed, is modulated or controlled in accordance with the video-frequency voltages impressed upon the input circuit of this device. The saw-tooth scanning waves developed by the generators 19 and 20 and applied to the scanning elements of device 18, serve to cause the beam to be deflected so as to trace a rectilinear scanning pattern on the target of the reproducing device 18 and thereby reconstruct the transmitted scene. The generators 19 and 20 are synchronized with the corresponding scanning apparatus at the transmitter by synchronizing pulses appearing in the output circuit of the amplifier 17 and applied thereto by way of suitable synchronizing-signal-separating apparatus which may be included in the units 19 and 20.

Referring now more particularly to the video-frequency signal-translating system embodying the present invention, the amplifier stage 17 comprises a vacuum-tube amplifier 21 which may be of the triode type, as shown, or any other suitable type. The input circuit of this tube is coupled to the output circuit of the amplifier 16 by way of a suitable coupling condenser 22 and grid-leak resistor 23. A load resistor 24 of the adjustable voltage-divider type is included in the output circuit of the tube 21, together with a suitable source of operating voltage, for example, a battery 25.

For the purpose of developing a unidirectional-bias voltage proportional to the peak value of the signal on the black side of its zero axis, there is provided means coupled to the output circuit of tube 21 for deriving only a predetermined portion of the alternating current component therein. This means comprises condenser 28 and resistor 27 connected in series across a portion of the voltage-divider resistor 24 by way of an adjustable tap 24a and a diode rectifier 26 which is coupled to the circuit 28, 27 and is responsive to the peak value of the signal on one side, that is, the black side, of the zero axis for deriving a unidirectional voltage proportional thereto. The load circuit of the rectifier comprises a parallel-connected resistor 29 and condenser 30, the positive terminal of this resistor being connected to the control grid of the tube 21 by way of the grid-leak resistor 23. A source of fixed-negative-bias voltage, for example, a battery 31 may be connected in series with the resistor 29, as shown.

In the operation of the system of the present invention, the signal, including combined video-frequency components and synchronizing-signal components having amplitude values outside the range of the video-frequency components, is applied from video-frequency amplifier 16 to the input circuit of the tube 21 and may be considered as unstabilized, or as having lost its background-illumination component, and as so poled that the signal components representing black extend in the negative direction. That is to say, by the passage of the signal through alternating current coupling elements, such as condensers in the amplifier 16 and condenser 22, the video-frequency signal centers itself about an equal-area axis. However, the background-illumination component is represented in this unstabilized signal by the peak value thereof on the black side of the zero axis. While the coupling condenser 22 and grid leak 23, if given appropriate impedance values, would serve in the conventional manner to develop a unidirectional-grid-bias voltage which would serve approximately to reinsert the background-illumination component, due to the selection of optimum values of the leak resistor 23 and condenser 22, as dictated by other circuit requirements, the load on the grid circuit and its time constant is such that this bias voltage is not a precise measure of the peak value of the video-frequency signal in the negative direction so that the background-illumination reinsertion is not complete.

By adjusting the tap 24a on the adjustable voltage-divider resistor 24, a predetermined portion of the output signal voltage of the tube 21 is impressed upon the diode rectifier 26, a reversal in polarity being effected by tube 21. The rectifier, in turn, serves to develop across its load circuit 29, 30 from this reversed video-frequency signal, a unidirectional-bias voltage

proportional to the peak value of the signal on the black side of its zero axis, that is, in this case, the peak value of the signal in the positive direction. This voltage is applied in series with the grid-leak resistor 23 in the input circuit of tube 21 and in opposition to the fixed-negative-bias voltage supplied from the source or battery 31. It will be appreciated that the signal in the output circuit of the tube 21, due to the amplification in this tube, is substantially of greater amplitude than the signal impressed upon the input circuit of the tube. By properly adjusting the tap 24a on the voltage-divider resistor 24, therefore, a portion of the signal-output voltage may be selected, which is of such value that the unidirectional voltage developed therefrom by the rectifier is substantially equal to the peak value of the signal input to the amplifier 17 on the black side of its zero axis. This unidirectional voltage, therefore, represents a precise measure of the background-illumination component of the signal voltage and, being applied to the input circuit, causes this component to be reinserted in the signal translated by the system; that is, to stabilize the signal precisely on its peaks in the negative direction. Where the signal, as applied to the input circuit of the tube 21, has a polarity opposite to that described above, so that its components representing black extend in the positive direction, it is only necessary that the polarity of the diode 26 be reversed to obtain proper operation under this condition.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A video-frequency signal-translating system comprising, an amplifier having an input circuit adapted to have impressed thereon an unstabilized video-frequency signal having its background illumination represented by the peak value thereof on one side of its zero axis, a grid-leak resistor for said amplifier, an output circuit for said amplifier, means coupled to said output circuit for deriving only the alternating current component therein, means coupled to said last mentioned means and responsive to said peak value of said signal on one side of its zero axis for developing a unidirectional voltage proportional thereto, and means for applying said unidirectional voltage to said input circuit in series with said grid-leak resistor to reinsert the background-illumination component in the signal translated by said system.

2. A video-frequency signal-translating system comprising, an amplifier having an input circuit adapted to have impressed thereon an unstabilized video-frequency signal having its background illumination represented by the peak value thereof on one side of its zero axis, a grid-leak resistor for said amplifier, an output circuit for said amplifier, adjustable means included in said output circuit for selecting only a predetermined portion of the alternating component of the signal-output voltage of said amplifier, means responsive to said peak value of said selected signal on one side of its zero axis for developing from the selected signal voltage

5 a unidirectional voltage substantially equal thereto, and means for applying said unidirectional voltage to said input circuit in series with said grid-leak resistor to reinsert the background-illumination component in the signal translated by said system.

3. A video-frequency signal-translating system comprising, an amplifier having an input circuit adapted to have impressed thereon an unstabilized video-frequency signal having its background illumination represented by the peak value thereof on one side of its zero axis, a grid-leak resistor for said amplifier, an output circuit for said amplifier, means including an adjustable voltage-divider resistor included in said output circuit for selecting only a predetermined portion of the alternating component of the signal-output voltage of said amplifier, means responsive to said peak value of said selected signal on one side of its zero axis for developing from the selected signal voltage a unidirectional voltage substantially equal thereto, and means for applying said unidirectional voltage to said input circuit in series with said grid-leak resistor to reinsert said background-illumination component in said signal translated by said system.

4. A video-frequency signal-translating system comprising, an amplifier having an input circuit adapted to have impressed thereon an unstabilized video-frequency signal having its background illumination represented by the peak value thereof on one side of its zero axis, a grid-leak resistor for said amplifier, an output circuit for said amplifier, means coupled to said output circuit for deriving only the alternating current component therein, a diode rectifier coupled to said last-mentioned means and responsive to said peak value of said signal on one side of its zero axis for developing a unidirectional voltage proportional thereto, and means for applying said unidirectional voltage to said input circuit in series with said grid-leak resistor to reinsert the background-illumination component in the signal translated by said system.

5. A video-frequency signal-translating system comprising, an amplifier having an input circuit adapted to have impressed thereon an unstabilized video-frequency signal having its background illumination represented by the peak value thereof on one side of its zero axis, a grid-leak resistor for said amplifier, means for applying a fixed-bias voltage to said input circuit, an output circuit for said amplifier, means coupled to said output circuit for deriving only the alternating current component therein, means coupled to said last-mentioned means and responsive to said peak value of said signal on one side of its zero axis for developing a unidirectional voltage proportional thereto, and means for applying said unidirectional voltage to said input circuit in series with said grid-leak resistor to reinsert the background-illumination component in the signal translated by said system.

6. A video-frequency signal-translating system comprising, an amplifier having an input circuit adapted to have impressed thereon an unstabilized video-frequency signal including combined video-frequency components and synchronizing-signal components having amplitude values outside the range of the video-frequency components, the background illumination being represented by the peak value of the signal on the side of its axis corresponding to black, a grid-leak resistor for said amplifier, an output cir-

cuit for said amplifier, means coupled to said output circuit for deriving only the alternating current component therein, means coupled to said last-mentioned means and responsive to said peak value of said signal on the black side of its zero axis for developing a unidirectional voltage proportional thereto, and means for applying said unidirectional voltage to said input circuit in series with said grid-leak resistor to reinsert the background-illumination component in the 10 signal translated by said system.

7. A video-frequency signal-translating system comprising, an amplifier having an input circuit adapted to have impressed thereon an unstabilized video-frequency signal including combined video-frequency components and synchronizing-signal components having amplitude values extending outside the range of the video-frequency components on one side of its zero axis, a grid-leak resistor for said amplifier, an output circuit for said amplifier, means coupled to said output circuit for deriving only the alternating current component therein, means coupled to said last-mentioned means and responsive to said peak value of said synchronizing-signal components for developing a unidirectional voltage proportional thereto, and means for applying said unidirectional voltage to said input circuit in series with said grid-leak resistor to reinsert the background-illumination component in the signal translated by said system.

8. A video-frequency signal-translating system comprising, an amplifier having an input circuit adapted to have impressed thereon a video-frequency signal including combined video-frequency components and synchronizing-signal components having amplitude values extending outside the range of the picture components on one side of its zero axis, a grid-leak resistor for said amplifier, an output circuit for said amplifier, means coupled to said output circuit for deriving only the alternating current component therein, a diode rectifier coupled to said last-mentioned means and responsive to said peak value of said synchronizing-signal components for developing a unidirectional voltage proportional thereto, and means for applying said unidirectional voltage to said input circuit in series with said grid-leak resistor to reinsert the background-illumination component in the signal translated by said system.

15 9. A video-frequency signal-translating system comprising, an amplifier having an input circuit adapted to have impressed thereon a video-frequency signal including combined video-frequency components and synchronizing-signal components having amplitude values extending outside the range of the picture components on one side of its zero axis, a grid-leak resistor for said amplifier, an output circuit for said amplifier, means coupled to said output circuit for deriving only the alternating current component therein, a diode rectifier coupled to said last-mentioned means and responsive to said peak value of said synchronizing-signal components for developing a unidirectional voltage proportional thereto, and means for applying said unidirectional voltage to said input circuit in series with said grid-leak resistor to reinsert the background-illumination component in the signal translated by said system.

JOHN C. WILSON.
